UNITED STATES PATENT OFFICE

2,276,588

PEDESTAL

Lawrence M. Michelson, Clayton, Mo., assignor to
 Duro Chrome Corporation, St. Louis, Mo., a cor-
 poration of Missouri

Application March 25, 1940, Serial No. 325,815

8 Claims. (Cl. 155—134)

This invention relates generally to certain new and useful improvements in pedestals and, more particularly, to pedestals or bases for stools, chairs, and similar seating devices commonly employed at soda fountains, bars, restaurant counters, and the like.

Up to the present time, pedestals and stool bases of the type stated have conventionally been fabricated from gray iron castings. Such pedestals or stool bases, however, are extremely heavy and consequently the shipping cost is relatively high. In addition, castings of this type are rough and frequently surface-pitted, necessitating various expensive surface finishing operations before the casting can be plated, enameled, sprayed, or otherwise decoratively coated. Cast-iron stool bases of this character, furthermore, are frequently defective and a relatively large number of them must be rejected from each lot of castings. Finally, the completed castings are somewhat brittle and frequently crack, chip, or break when roughly handled by workmen during installation at the location of ultimate use, impeding the progress of the installation and interfering with its completion.

My invention hence has for its primary objects the provision of a unique and improved form of pedestal or stool base which is simple and economical in construction, which is extremely light in weight, which is tough, durable, and non-brittle, which may readily be adapted to a wide variety of external decorative designs at extremely low cost, which may be quickly and conventionally installed, and which is otherwise highly satisfactory in the performance of its stated functions.

And with the above and other objects in view, my invention resides in the novel features of form, construction, arrangement, and combination of parts presently described and pointed out in the claims.

In the accompanying drawings (2 sheets)—

Figure 1 is a perspective view of a counter stool constructed in accordance with and embodying my present invention;

Figure 2 is a vertical elevational view, partly broken away and in section, of the stool base of my invention;

Figure 3 is a fragmentary perspective view of the inner supporting structure of the stool base;

Figure 4 is a fragmentary horizontal sectional view of the stool base, taken approximately along the line 4—4, Figure 2;

Figure 5 is a fragmentary view, partly broken

away and in section, of a modified form of stool base of my invention; and

Figure 6 is a fragmentary vertical sectional view of the modified form of stool base, taken approximately along the line 6—6, Figure 5.

Referring now in more detail and by reference characters to the drawings, which illustrate practical embodiments of my present invention, A designates a stool base including an outer shell 1 pressed, drawn, or spun from relatively thin metal preferably capable of taking a high surface polish or such other suitable ornamental coating as may be desired and provided at its lower end with a diametrically enlarged outwardly flaring base flange or bell 2, which may have any suitable shape depending upon the decorative design desired. Mounted co-axially within and extending through the outer shell 1, is a tubular steel shaft 3 having an inwardly rolled annular bead 6 and being provided at its upper end with a loose-fitting concentric washer 4 diametrically reduced along its periphery for snug-fitting engagement with the upper open end of the outer shell 1.

Pressed upon the upper projecting end of the tubular shell shaft 3, is an annular spacing collar 5 endwise supporting a conventional seat-operating cam 6, the steel shaft 3 being peened over around its upper projecting margin in the formation of a retaining lip 7 for holding the cam 6 securely in place, all as best seen in Figure 2 and for purposes presently fully appearing.

At its lower end, the tubular steel shaft 3 is internally provided with a centrally bored collar 8 preferably secured in place by a fillet weld 9 or other suitable means and welded or otherwise suitably mounted upon the outer surface of the tubular shaft 3 adjacent its lower end, is a plurality or radially extending channel-shaped foot members 10 projecting obliquely downwardly and being cut off in the provision of floor-engaging surfaces 11, all of which obviously lie in a common plane at right angles to the longitudinal axis of the tubular steel shaft 3. In this connection, it will also be noted that the length, angle of inclination, and size generally of the foot members 10 are preferably selected for close-fitting wholly concealed disposition within the lower flaring bell portion 2.

It will, of course, be evident that the tubular steel shaft 3 is initially fabricated and the outer shell 1, collar 4, spacing collar 5, and seat operating cam 6 are assembled therewith, whereupon the projecting end or margin of the tubular shaft 3 is upset in the provision of a retaining flange

1, holding the several parts securely together in a unitary structure. The stool base A may be installed substantially in the same manner as disclosed in my previously granted patent, No. 1,829,960, granted November 3, 1931, that is to say, a suitable stud 12 is embedded head down in the floor F with a sufficient length of its threaded end or shank projecting upwardly to extend through the apertured collar 8. A suitably elongated socket wrench is inserted through the tubular shaft 3 and a retaining nut 13 is installed for clampingly securing the entire structure tightly upon the floor F.

Finally, as diagrammatically indicated in dotted lines in Figure 2, a suitably sized conventional stool swivel 9 is disposed within the upper end of the steel shaft 3 in endwise abutment upon the annular shoulder or bead b for rotatably supporting a conventional seat-tripod or spider S and upholstered seat B, all as best seen in Figures 1 and 2.

It will, of course, be evident in this connection that the tubular shaft 3, being fabricated of steel tubing, is extremely strong and yet comparatively light in weight. Similarly, the outer shell 1 may be fabricated of very light materials and, therefore, will lend itself to a wide variety of different decorative designs and finishes and will also be relatively light in weight. From this, it will be evident that stool bases constructed in accordance with my present invention will be inexpensive, durable, and light in overall weight. Thus, material savings, due to lower shipping costs, may be effected, and greater durability, low finishing and surfacing costs, and wide range of decorative design will be achieved.

I may also provide a modified form of stool base A' including an outer shell 1' having a flaring bell portion 2' and a tubular steel shaft 3', all substantially identical with the corresponding parts of the previously described stool base A. Welded or otherwise secured upon the lower end of the shaft 3', is a spun or stamped steel base-disk 14 integrally including an upstanding peripheral flange 15 and a centrally disposed upstanding shaft-embracing collar 16. Spot-welded around its peripheral margin to the upper face of the base-disk 14, is a conical or dished bracing member 17 centrally apertured for snug-fitting embracing engagement around the disk-collar 16 and welded with the base-disk 14 to the shaft 3'. In this connection, it may be pointed out that the base-disk 14 and bracing member 17 are preferably sized and shaped for close-fitting concealed disposition within the flaring bell portion or base flange 2' of the outer shell 1', all as best seen in Figures 5 and 6.

It should be understood that changes and modifications in the form, construction, arrangement, and combination of the several parts of the pedestal may be made and substituted for those herein shown and described without departing from the nature and principle of my invention.

Having thus described my invention, what I claim and desire to secure by Letters Patent is:

1. A stool base including an outer shell provided at one end with a diametrically enlarged base flange and at its other end with a centrally apertured collar, an inner tubular shaft extending interiorly through the outer shell and projecting at one end outwardly through the collar and terminating at its other end interiorly of the base flange and being provided at such end with floor-engaging means disposed within the confines of the base flange for supporting the entire

structure in upright position, and means fixed upon the projecting end of the inner shaft and abuttingly engaging the outer face of the collar co-operating with the floor-engaging means for securing the inner shaft, the collar, and the outer shell together in the formation of a unitary structure.

2. A stool base comprising an upright tubular inner member, an outer tubular member fixed to and disposed concentrically around the inner member, an upwardly and inwardly tapering disk-like member having a collar embracingly engaged around an end of the inner member in the formation of a supporting base, and bracing means disposed above the disk-like member and secured between the inner member and the disk-like member.

3. A stool base comprising an upright tubular inner member, an outer tubular member fixed to and disposed concentrically around the inner member, an upwardly tapering conical base member embracingly engaged around an end of the inner member in the formation of a supporting base, and an upwardly tapering conical bracing member disposed above the base member and secured between the inner member and the base member.

4. A stool base including an outer shell provided at one end with a diametrically enlarged bell and at its other end with a centrally apertured collar, an inner tubular shaft extending interiorly through the outer shell and projecting at one end outwardly through the collar and terminating at its other end interiorly of the bell and being provided at such end with a conical disk secured to the shaft and disposed snugly within the confines of the bell for supporting the entire structure in upright position, and means fixed upon the projecting end of the inner shaft and abuttingly engaging the outer face of the collar for securing the inner shaft, the collar, and the outer shell securely together in the formation of a unitary structure.

5. A stool base comprising an inner tubular shaft provided at its upper end with a socket for rotatably receiving a seat swivel and at its lower end with a centrally apertured internal collar for receiving a floor stud, a downwardly flaring conical base-disk having an axially upstanding collar fitting snugly around and secured to the lower end of the shaft in the provision of a floor-engaging support, a conical brace-disk of substantially greater angular inclination to the shaft axis than the base-disk and being peripherally secured at its outer margin to the base-disk and at its inner margin to the base-disk collar in the formation of a stiffening brace, and a tubular outer shell disposed co-axially around and secured at its upper end to the upper end of the shaft and provided at its lower end with a diametrically enlarged bell for concealably embracing the base-disk and the associated brace-disk.

6. A stool base comprising an inner tubular shaft provided at its upper end with a socket for rotatably receiving a seat swivel and at its lower end with a centrally apertured internal collar for receiving a floor stud, a downwardly flaring conical base-disk secured to the lower end of the shaft in the provision of a floor-engaging support, a conical brace-disk of substantially greater angular inclination to the shaft axis than the base-disk and being peripherally secured at its outer margin to the base-disk and at its inner margin to the shaft in the formation of a stiffening brace, and a tubular outer shell disposed co-

axially around and secured at its upper end to the upper end of the shaft and provided at its lower end with a diametrically enlarged bell for concealably embracing the base-disk and the associated brace-disk.

7. A stool base comprising an inner tubular shaft provided at its upper end with a socket for rotatably receiving a seat swivel and at its lower end with means for engagement with a floor stud, and base means including a pair of overlying downwardly and outwardly flaring members secured to the lower end of the shaft and to each other, the uppermost of said members being of substantially greater slope than the other of said members in the formation of a stiffening brace.

8. A stool base including an outer shell pro-

vided at one end with a diametrically enlarged base flange, an inner shaft extending through the outer shell and terminating at its one end interiorly of the base flange, said shaft being provided at such end with floor engaging means disposed within the confines of the base flange, said floor engaging means bearing against the underside of the base flange for holding the outer shell off the floor whereby the entire structure may be supported in upright position by the shaft and its associated floor engaging means, and means upon the opposite end of the shaft extending radially outwardly therefrom and secured to the outer shell for clampingly holding the outer shell between said means and the floor engaging means.

LAWRENCE M. MICHELSON.
